UNITED STATES PATENT OFFICE.

BENJAMIN SAMUEL HAMPTON HARRIS, OF GREENVILLE, SOUTH CAROLINA, ASSIGNOR
TO HARRIS-BROCKMAN MFG. CO., INC., OF GREENVILLE, SOUTH CAROLINA, A COR-
PORATION OF SOUTH CAROLINA

HYDRO-PNEUMATIC PUMP.

1,259,979.

Specification of Letters Patent.

Patented Mar. 19, 1918.

Application filed February 27, 1917. Serial No. 151,255.

To all whom it may concern:

Be it known that I, BENJAMIN S. H. HARRIS, a citizen of the United States, and a resident of Greenville, in the county of Greenville and State of South Carolina, have invented a certain new and useful Improvement in Hydropneumatic Pumps, of which the following is a specification.

My present invention relates generally to pumps, and more particularly to a pump in the nature of a compressed air water elevator, without pistons, and capable of use without undue wear even in localities where sand is frequently carried with the fluid to be pumped, my primary object being the provision of a pump which will be simple, strong and durable, capable of effective and efficient operation, and which will permit of ready accessibility to its several working parts for purposes of repair and substitution.

A further object of my invention is to provide a pump including a single cylinder or casing containing the fluid to be pumped, and from which such fluid is to be forced to the place of utilization by other fluid under pressure, and wherein the several operations of the pump are controlled, through simple effective means, and by the fluid being pumped, in the use thereof.

In the accompanying drawings illustrating my invention, and forming a part of this specification:

Figure 1 is a top plan view;

Fig. 2 is a vertical longitudinal section taken substantially on line 2-2 of Fig. 1.

Fig. 3 is a detail horizontal section taken substantially on line 3-3 of Fig. 2;

Fig. 4 is a detail vertical section taken substantially on line 4-4 of Fig. 1, with the casing removed;

Fig. 5 is a detail vertical section through a portion of the casing head, taken substantially on line 5-5 of Fig. 1;

Fig. 6 is a detail horizontal section taken substantially on line 6-6 of Fig. 2,

Fig. 7 is a similar view taken substantially on line 7-7 of Fig. 2,

Fig. 8 is a detail vertical section through the chamber of the upper float, and

Fig. 9 is a detail horizontal section taken substantially on line 9-9 of Fig. 2.

Referring now to these figures, my invention contemplates the provision of a substantially cylindrical casing 10, which, as best seen in Fig. 2, is provided with an intake member 11 at its lower end, preferably threaded thereto and having a depending screen-covered cage 12, above which is a substantially flat valve 13 through which water is admitted from the cage 12, the latter of which is designed to prevent the entrance of extraneous matter.

As seen by a comparison of Figs. 2 and 9, an inner valve cage 14 is secured to the intake member 11 by vertical bolts 15, said valve cage 14 providing for limited upward movement of the valve 13 with respect to its seat 16, downwardly against which it is movable, under pressure, to prevent the exit of fluid to be pumped, after the fluid has entered with the valve 13 in its upper position, the cage 14 being open at its sides.

The upper end of the casing 10 is closed by a casing head 17, preferably threaded thereto, and into which are threaded air inlet and outlet nipples 18 and 19 respectively, having valve seats 20 and 21 as best seen in Fig. 4, and providing for the connection therein of air supply and exhaust pipes (not shown).

The casing head 17 is also provided with a cavity 22, communicating with an upper water outlet opening 23, and with the upper ends of a pair of spaced depending water outlet pipes 24, the latter of which are anchored at their upper ends within the lower portion of the head 17, and have their lower ends opening into the casing 10 at a point adjacent the lower end of the latter, as seen at 25 in Fig. 2, said lower ends of said pipes being secured to and supporting a lower horizontal plate 26, seen in Figs. 2, 3, and 6.

Upon the upper outer face of the head 17, around the water outlet opening 23, is a valve casing 27, to which a service pipe and the like may be connected, having therein a vertically movable valve member 28, seated downwardly upon the upper outer surface of the head 17 around the said opening 23.

Intermediately of the ends of the pipes 24 and at a point substantially midway the length of the casing 10, said pipes support a bracket 29, horizontally between them, in

which a lever 30 is pivotally mounted at one end at 31, and has its opposite free end projecting between stops 32 and 33, which limits its vertical shifting movement upon its pivot 31, said free end of said lever having upper and lower cavities 34 and 35. The lever 30 is also provided with an intermediate head 36 having upper and lower notches 37 in which are engageable the angular extension 38 of upper and lower latch members 39 and 40, latch member 39 engaging the lever as seen in Fig. 2, with the lever in its lowermost position, and latch member 40 being designed to similarly engage the lever when the latter is in its upper position, and being to this end provided with a weighted arm 41.

Adjacent its pivot 31, the lever 30 has a cross pin 42, extending through, and pivotally connecting the lower ends, of a pair of upwardly extending arms 43 and 44, each of which is provided with an upper threaded socket 45, by means of which the lower threaded end 46 of its respective valve actuating rod 47, 48, is adjustably connected, the connection so made and of the character stated being locked by means of a nut 49 upon each rod above the socket 45.

The valve actuating rods 47 and 48 extend upwardly in spaced parallel relation to respectively actuate the air intake and outlet valves, of which the air inlet valve 50 is held downwardly in closed position against its seat 20, by means of the pressure of the air, except when the rod 47 is elevated to project its upper polygonal end 51 upwardly against and unseat said valve, valve 50 as seen in Fig. 4, being movably disposed in the air intake nipple 18 below a dirt receiving cage 52 disposed therein and having apertures 53 through which the air passes when valve 50 is open.

The valve actuating rod 48, which is moved simultaneously with the rod 47, upon movement of lever 30, controls the air outlet valve 54 disposed at its upper end, and within the lower cylindrical portion of the air outlet nipple 19, below the valve seat 21 before mentioned, the said lower portion of the nipple 19 having lateral openings 55 through which air may exhaust from the casing 10 with the valve 54 in its lowermost position, as shown in Fig. 4. The upper end of the rod 48, however, is slotted as at 56 in Fig. 4, to receive a cross pin 57 of the valve 54, and it is obvious that, by this connection, the valve 54 is capable of limited movement relative to, and in, the direction of the length of, the said rod, and under tension of a spring 58 coiled about the upper portion of the rod and compressed between the lower end of the valve 54 and an adjustable set collar 59 upon the rod below the valve.

55 Within the lower portion of the casing

10 is disposed a float 60, which in its lowermost position rests upon a pad 61 upon the lower supporting plate 26, and which in its vertical movements, is guided by the water outlet pipes 24 and the casing 10 at one side, as shown in Fig. 6. The float 60 is provided with an upwardly projecting stem 62, as seen in Fig. 2, the upper portion of which extends loosely through an opening in the latch member 40 and has a rounded upper extremity projecting into the lower cavity 35 of the lever 30. The stem 62 is also provided with a set collar adjustably secured upon its upper portion above the latch member 40, for a purpose to be presently described.

To the lower surface of the casing head 17 within the casing 10, is secured the upper portion of a float chamber 64, the upper edge of which is cut away to provide a space 65 between the same and the lower surface of the head 17, through which the fluid to be pumped may find its way into the said chamber, the lower rounded end of the chamber having a central opening 66 and 90 being otherwise closed for a purpose to be presently described.

Within the float chamber 64 is disposed a float 67, having a depending stem 68 projecting downwardly through the opening 66, and provided with a valve ring 69 which, in the lowermost position of the float 67, engages the lower inner surface of the float chamber 64 around the opening 66, to close the latter against the inlet of the fluid to be pumped. The lower end of the float stem 68 depends loosely through an opening in the latch member 39 and has its lower rounded extremity projecting into the upper cavity 34 of the lever 30, said lower end of said stem being further provided with a set collar adjustably secured thereon below the said latch member 39, for a purpose to be presently described.

Thus, with the parts in the position shown in Fig. 2 for the intake of the fluid to be pumped, said fluid is admitted through the screened lower cage 12, its pressure operating to raise the valve member 13 to permit the water to enter the casing 10, the latter of which is in practice submerged within the fluid to be pumped. In this position, it will be noted that the air outlet valve 54 is in its lower open position, permitting the air within the casing 10 to readily exhaust therefrom, as the water rises, this operation continuing without action of the parts until the water reaches a level above the upper open end of the float chamber 64, due to the fact that lever 30 is latched by the latch member 39, as seen, which prevents the lower float 60 from rising.

As soon, however, as the fluid overflows into the upper float chamber 64, the float 67 rises therein, and upon its initial movement 130

in this direction, the valve ring 69 being lifted from its closed position, the pressure of water through the opening 66 hastens the movement of the float. As soon as the float 5 67 rises sufficiently to bring its set collar 70 into engagement with the latch member 39, the latter is lifted and the lever 30 released, so that the upward tendency of the lower float 60 raises the free end of the lever 30 10 and forces both of the valve actuating rods 47 and 48 upwardly, the upper end of the former striking the air inlet valve 50 at the same instant the valve 54 seats against the seat 21, so that during the further movement of the rod 47 to raise the valve 50 to open position, the corresponding movement of rod 48 will be permitted by virtue of the pin and slot connection at 56, 57.

Thus, with the air intake valve 50 open 20 and valve 54 closed, the pressure of the air upon the surface of the fluid within the casing 10 will force the fluid up and out through the water outlet pipes 24, the cavity 22 of the head 17, and will raise valve 28 25 to permit of passage of the water outwardly through the service pipe or other connection secured to the valve casing 27, this operation continuing until the water level falls within the casing 10 to a point permitting the lower float 60 to descend and release the latch member 40, engaged during the outlet of water from the casing, with the lower notch 25 the lever 30, to lock the lever in its upper position against the stop 32. When the latch member 40 is released the upper float 67 descends of course to the position shown in Fig. 2, lowering the lever 30 and causing corresponding lowering movement of the valve-actuating rods 47 and 48 to the position shown in Fig. 4.

It is obvious from the foregoing that my invention provides a simple durable arrangement which will be effective and efficient in use for the purposes first above stated, as well 45 as one to the various parts of which ready access may be had by virtue of the connection of the casing head 17 with the casing and the fact that the several operating parts are supported by this head and depend 50 freely within the casing 10, so that they may be withdrawn therefrom, along with the head 17, whenever desired.

I claim:

1. A pump of the character described, 55 comprising a casing having a water intake valve at its lower end, a head closing the upper end of the casing, having a valved water outlet, a valved air intake and valved air outlet, a pair of water outlet pipes depending from said head within the casing and opening at their lower ends adjacent the lower end of said casing, valve actuating rods depending from the air intake and outlet valves, a lever actuating said rods, and having limited movement within the casing, a support for said lever carried by said wa-

50 ppes, latch members for locking said lever against movement, and lever actuating floats in the casing having stems engaging said lever and provided with means for releasing 70 said latch members.

2. A pump of the character described, comprising a casing having a water intake valve at its lower end, a head closing the upper end of the casing, having a valved water outlet, 75 a valved air intake and valved air outlet, a pair of water outlet pipes depending from said head within the casing and opening at their lower ends adjacent the lower end of said casing, valve actuating rods depending from the air intake and outlet valves, a lever actuating said rods, and having limited movement within the casing, a support for said lever carried by said water pipes, latch members for locking said lever against movement, and lever actuating floats having means to release said latch members, the lower of which floats is movable along, and guided by, the lower portions of said water pipes.

3. A pump of the character described, comprising a casing having a water intake valve at its lower end, a head closing the upper end of the casing, having a valved water outlet, 90 a valved air intake and valved air outlet, a pair of water outlet pipes depending from said head within the casing and opening at their lower ends adjacent the lower end of said casing, valve actuating rods depending from the air intake and outlet valves, a lever actuating said rods and having limited movement within the casing, a support for said lever carried by said water pipes, latch members for locking said lever against movement, lever actuating floats having means to release said latch members, the lower of which floats is movable along, and guided by, the lower portions of said water pipes, and a supporting plate secured to and carried by the lower ends of the water pipes 100 and upon which the lower float rests in its lowermost position.

4. A pump of the character described comprising a casing having a water intake valve at its lower end, a head closing the 115 upper end of the casing having a valved water outlet, a valved air intake and valved air outlet, a pair of water outlet pipes depending from said head within the casing and opening at their lower ends adjacent the lower end of said casing, valve actuating rods depending from the air intake and outlet valves, a lever actuating said rods and having limited movement within the casing, a support for said lever carried by said water pipes, latch members for locking said lever against movement, and upper and lower lever actuating floats in the casing, having means for releasing said latch members, and a casing in which the upper float 130

is movable, carried by the said casing head and opening at its upper end adjacent the lower inner surface of the head.

5. A pump of the character described, comprising a casing having a water intake at its lower end, a head closing the upper end of the casing and having a valved water outlet, said head also having a valved air intake and a valved air outlet, a pair of water outlet pipes depending from said head within the casing and opening at their lower ends adjacent the lower end of said casing, valve actuating rods depending from the valves of the air intake and outlet, a lever actuating the same and having limited movement in the casing, a bracket carried by the said water outlet pipes intermediate their ends, and in which the said lever is pivoted, having stops for the levers, latch members mounted in the said bracket and movable to engage and lock the said lever at the limit of its movements, and lever actuating floats in the casing having stems engaging the said lever, said stems extending through portions of the said latch members and having set collars thereon for engaging and releasing the latch members in the movement of the floats.

10. A pump of the character described, comprising a casing having a water intake at its lower end, a head closing the upper end of the casing and having a valved water outlet, said head also having a valved air intake and a valved air outlet, a pair of water outlet pipes depending from said head within the casing and opening at their lower ends adjacent the lower end of said casing, valve actuating rods depending from the valves of the air intake and outlet, a lever actuating the same and having limited

movement in the casing, a bracket carried by the said water outlet pipes intermediate their ends and in which the said lever is pivoted, having stops for the levers, latch members mounted in the said bracket and movable to engage and lock the said lever at the limit of its movements, and lever actuating floats in the casing having stems engaging the said lever, said stems extending through portions of the said latch members and having set collars thereon for engaging and releasing the latch members in the movement of the floats.

15. A pump of the character described comprising a casing having a valved fluid intake at its lower end, and a valved water outlet at its upper end, said casing also having at its upper end a valved air inlet and a valved air outlet, fluid controlled floats movable in said casing, a lever actuated by the said floats and having connections for controlling the valves of the air inlet and outlet, and connections for controlling said lever in its movements also actuated by the said floats.

20. A pump of the character described comprising a casing having a valved fluid intake at its lower end, and a valved water outlet at its upper end, said casing also having at its upper end a valved air inlet and a valved air outlet, fluid controlled floats movable in said casing, a lever actuated by the said floats and having connections for controlling the valves of the air inlet and outlet, means for locking the said lever, and means carried by the floats for releasing the said locking means.

BENJAMIN SAMUEL HAMPTON HARRIS.
